United States Patent Office

Des. 178,949
Patented Oct. 16, 1956

178,949

DRESS

Harvey Berin, New York, N. Y.

Application August 13, 1956, Serial No. 42,587

Term of patent 3½ years

(Cl. D3—26)

Fig. 1.

Fig. 2.

I claim:

The ornamental design for a dress, substantially as shown.
